UNITED STATES PATENT OFFICE

GEORGE E. DEAN, OF GRAND RAPIDS, MICHIGAN, ASSIGNOR TO CHARLES G. WILLETT,
OF GRAND RAPIDS, MICHIGAN

ROAD GRADER

Application filed January 2, 1931. Serial No. 506,152.

This invention relates to road scrapers of the type which are now used on and below trucks on roads for the purpose of scraping the road to level or smooth the same or for removing snow or the like from the road in the winter time.

In road scrapers of this type it has been common to mount a single scraper blade on a rock shaft which in turn has been carried on suitable hangers from an upper supporting beam and the beam is mounted with reference to the truck chassis frame so that it can be shifted to different angles to the longitudinal axis of the frame or may be reversed in position so as to scrape to the same side of the road in either direction of movement of the truck. It has further been common to operate the rock shaft by a hydraulic operated piston so as to raise or lower the scraper blade, lifting it into inoperative position when it is not to be used and forcing it downwardly against the road surface when it is used.

The present invention has as one of its primary objects and purposes the provision of double aligned rock shafts each carrying and supporting a pivotally mounted blade thereon. These blades are independently mounted with reference to each other and hence any shocks which may be had by one of the blades will not be transmitted to the other blade. Thus the jars and vibrations will be transmitted only to one side of the machine, which is obviously advantageous, and furthermore, should one blade become broken it may be replaced without the necessity of purchasing and installing an entirely new set of blades.

Another one of the principal features of my invention lies in my novel duplex blade installation together with its unique hydraulic control whereby the blades may be operated either independently or simultaneously to and from their operative position. In other words, one of the blades may be forced downwardly into an operative position whereas the other blade may be held clear of the ground.

A further object of the invention is to provide a novel hydraulic power and control means whereby the pressure fluid may be

transmitted to and allowed to escape from the hydraulic units as desired.

Yet another feature of my invention lies in the particular type of attachment between the scraper blade and its supporting plate whereby movement of the blade upwardly is absolutely prevented. That is, the action of the blade tending to move upwardly causes its clamping means to wedge against the supporting plate and thus prevent any such upward movement.

The nature and advantages of the invention will be better understood when the following detailed description is read in connection with the accompanying drawings, the invention residing in the construction, combination, and arrangement of parts as claimed.

The terms and expressions which I have employed are used as terms of description and not of limitation, and I have no intention, in the use of such terms, and expressions, of excluding any mechanical equivalents of the features shown and described, or portions thereof, but recognize that various structural modifications are possible within the scope of the invention claimed.

Referring to the drawings:—
Fig. 1 is a side elevation of a truck having my invention applied thereto, parts being broken away in order to expedite the showing.

Fig. 2 is a plan view of my invention, the body of the truck being removed.

Fig. 3 is a view of the rock shafts and their respective scraper blades, this view being taken on the line 3—3 of Fig. 1.

Fig. 4 is a view taken along the line 4—4 of Fig. 3.

Fig. 5 is a view of the turntable and its locking device looking from underneath the same.

Fig. 6 is an enlarged view showing the hydraulic control means together with the pump and its motor, and

Fig. 7 is an enlarged view of the four-way valve.

Similar numerals refer to similar parts throughout the several views.

The truck, shown in Fig. 1, is of any conventional construction, having a dump body 100

11, rear wheels 12, a cab 18 and side members 10, these side members forming the chassis of the truck frame. The side members 10 serve as the supporting members from which 5 the scraping apparatus is depended, in practice the spaced parallel bars 16 being adjustably supported by the vertically adjustable brackets 17.

As clearly shown in Figs. 1, 2 and 5, shoes 10 18 are adjustably mounted upon the spaced parallel bars 16 by means of studs threaded thereinto and extending upwardly between the bars 16 and through plates 19 positioned along the tops of the bars. The shoes 18 are 15 undercut as shown and overlap the rim of the turntable 20 or adjustable circle member whereby the turntable may be rotated within limits.

A beam 21 is firmly attached to the turntable 20 as by means of bolts 22 and hence these two members operate as one. A locking element or segment 23, see Fig. 5, is formed with a series of notches 24, these semi-circular openings being adapted to receive 23 the locking dog 25, this locking dog being rigid upon the lever 26 pivoted at 27. The pivot 27 is supported on the cross member 28, this cross member being adjustably mounted upon the spaced parallel bars 16 as 30 indicated at 29.

The free end of the lever 26 is engaged by the link or rod 30 which extends forwardly to connect with the manually operated lever 31, this last mentioned lever 31 being locked 35 in position by means of any suitable mechanism such as indicated at 32. See Fig. 1.

The cross member 21 has depending hangers 33 in which rock shafts 36 and 37 are rotatably mounted. These rock shafts are 40 of identical construction. Also, elements between the rock shafts and the scraper blade, as well as the hydraulic operating units therefor, are of substantially like construction, one being right-hand and the other being left-hand, and, hence, only one of these units will be described. Heavy springs 38 are connected at one end as by means of the plate and bolts 39, to the rock shaft and the lower ends 45 of these springs are fastened to the plate 40. The plate 40 has an opening 41 therein and a suitable scraper blade 42 is adjacent thereto. A bolt 43 passes through the plate 42 and a tapered washer member 44 is tightly held against the tapered face of the plate 40 50 by means of the nut 45. See Fig. 4. By proper manipulation of the locking means just recited the blade may be tightly clamped to the plate 40 and pressure exerted upwardly, as shown by the arrow, against the blade 55 will simply wedge the tapered washer member 44 against the tapered blade and hence prevent any upward movement whatsoever.

Clamps 50 have an ear 51 extending therefrom and are tightly clamped about a rock 60 shaft 37. A link 52 is pivoted to the ear 51

and a depending arm 53 is rigid with and extends from the crank shaft 54. See Figs. 1 and 3. The crank shaft 54 is mounted in L-shaped bearing brackets 55, these brackets or base plates resting upon and being supported by the cross beam 21. The base plate or bracket 55 serves to support the cylinder 56, having a piston 57 therein. A piston rod 58 extends from the piston and a cross head 59 serves to connect the rods 60 to arms 61 which are rigid with the crank shaft 54.

From the construction just set forth it will be apparent that movement of the piston 57 will cause the scraping blade 42 to move to and from its operative position. For instance, referring to Figs. 1 and 2, movement of the piston 57 towards the right will cause the cross head and the connecting rod 60 to turn the crank shaft 54 in a clockwise direction. This movement of the crank shaft 55 will be transmitted through the depending arm 53 to the link 52 which will, in turn, rotate the rock shaft 37 in a counter-clockwise direction so as to force the blade 42 downwardly against the surface on which it 90 is operated.

The cylinders 56 have pipes or conducting means 65 and 66 leading from their front and rear ends, respectively. These pipes or conducting means serve to transmit fluid pressure whereby the piston 57 may be forced along the cylinders 56 as desired.

Mounted in the cab of the truck, see Figs. 1 and 2, is a tank or receptacle or reservoir 67 having a suitable pump therein (not shown) and driven by a motor 68. An outlet pipe 69, having a check valve 70, transmits the fluid from the pump to one of the four ports of the four-way valve 71. See Fig. 7. The opposing port of the four-way valve 71 has a conducting means or pipe 72 which returns to the reservoir or tank from which the inlet to the pump leads. A suitable handle 73 is adapted to be manually operated whereby the plug 74 may be properly positioned. One of the two remaining ports of the four-way valve 71 has a pipe 75 leading downwardly, this pipe branching into branches 76 and 77, these branch connections leading through the valves 78 and 79 respectively. The valve 78 connects with a rearwardly extending pipe 80 which terminates in one of the laterally extending pipes 65, and the valve 79 connects with a rearwardly extending pipe 81 which terminates in the other laterally extending pipe 65.

The remaining port of the four-way valve leads to a downwardly extending pipe 82 which connects with a rearwardly extending pipe 83, this pipe being branched at the T 84. From this T 84 the previously referred to connections 66 extend into the front part of the cylinders 56. The pipes or connecting tubes 80, 81 and 83, which lead rearwardly to the operating cylinders 56, are 130

flexible as they are located between the hydraulic control device and the cross beam, these latter two elements having movement relative to each other.

5

The operation

The scraping blade mechanism is mounted upon the under frame of a truck in the usual manner and the motor 68 is operated. 10 This causes hydraulic pressure to be transmitted through the check valve 70, then through the pressure pipe 69 into the four-way valve 71 and then rearwardly through the pipes 75, 76, 77, 80 and 81 and finally 15 through the lateral pipes 65 into the rear of the cylinders 56 thus forcing the pistons 57 forwardly and pushing the blade 42 against the road. It will also be noted that the fluid passes through the valves 78 and 79 during 20 the movement just described.

It may be desirable to rotate the entire cross beam assembly from about its vertical pivot in order to properly position the scraper blades with respect to the road. That is, 25 the cross beam 21 may be in either of the dotted line positions as shown in Fig. 2, or at any intermediate position. And, furthermore, it is often times desirable to quickly change the cross beam from one position to 30 another. Previous to my invention it has been the practice to use separate and distinct means for accomplishing the above manipulation but due to my novel arrangement of parts I am able to expediently accomplish 35 this result by movement of the truck itself along the road. This is possible due to the fact that I have two separate scraping blades together with novel hydraulic operating means therefor.

40 Referring back to the valves 78 and 79, it will be apparent that one of these might be entirely closed, thus shutting off the fluid from the corresponding cylinder and thus preventing the corresponding blade from 45 contacting with the road surface. However, the other blade, upon actuation of the pressure motor 68, will be forced downwardly against the road and movement of the truck, either forward or backward as desired, will 50 cause the entire turntable and its depending parts to be rotated about its vertical pivot point. The lever 31 is operated to release the pivoted lever 26, carrying the locking dog 25, during the above manipulation and when 55 such is completed the turntable may be again locked in its desired position by return of the handle 31 to its original position whereby the locking dog 25 engages one of the notches in the segment on the turntable.

60 When it is desired to elevate the blades from the road the handle 73, of the four-way valve 71, is rotated so as to connect the pressure pipe 69 with the pipe 82, this causing the return pipe 72 to be connected with the pipe 75. Now, when the pump is operated the

pressure fluid will travel rearwardly through the pipe 83 and outwardly through the pipe 66 into the front end of the cylinder thus forcing the pistons 57 to the rear and raising the scraper blades from the road. If desired, one of the valves 78 or 79 might be kept closed during this manipulation with the consequence that one of the scraper blades remains in its original position as the fluid on the other side of the piston could not escape therefrom.

70 For instance, if the valve 78 were closed the fluid cannot escape through the outlet pipe 65 and the corresponding scraper blade would stay in its original position.

Having thus revealed this invention, I claim as new and desire to secure the following combinations and elements or equivalents thereof, by Letters Patent of the United States:

85 I claim:

1. In combination, a frame having two sets of spaced parallel members at either side thereof, two shoes located adjacent each of said sets of parallel members, bolt means extending from said shoes upwardly between said parallel members whereby the said shoes may be slid along the said parallel members, means for clamping each of the several shoes in its desired position, a turntable revolvably supported by said shoes and a beam rigidly attached to said turntable.

90 2. In a combination of elements as set forth in claim 1 the addition of means for locking the turntable against rotation for the purpose described.

95 3. In a device as recited in claim 1, the combination of a cross member attached to said sets of parallel members, a lever pivoted onto said cross member, means for oscillating said lever, a locking dog located on said lever at a point spaced from its pivot point and adjacent said turntable, said turntable having a locking element thereon, said locking element being recessed at a plurality of points to receive the locking dog whereby the turntable is held against rotative movement.

100 4. A road grader comprising a movable frame having parallel members thereon, a turntable located beneath and adjacent to the said parallel members, shoes fastened to the said parallel members and extending under the said turntable to revolvably support the same, a beam attached to the turntable and scraping means fastened to the beam.

105 5. A road scraper as set forth in claim 4 but in which the several shoes are adjustably mounted whereby the turntable and its beam may be bodily adjusted along the said parallel members for the purpose described.

110 6. A construction of the class described comprising a frame adapted to be moved in a forward direction over the ground, a cross member mounted thereon, hangers depend-

ing from the underside of the said cross members, a rock shaft revolvably mounted in said hangers, a scraper blade fastened to the rock shaft and extending downwardly and rearwardly to contact against the surface of the ground, an ear rigidly attached to the rock shaft and extending upwardly and rearwardly therefrom, a shaft, means to revolvably mount the last mentioned shaft rearwardly with respect to and spaced from the said ear, an arm, rigidly attached to the said shaft, extending downwardly therefrom, a link pivoted to said arm at one end and to the said ear at its other end, a second arm rigidly attached to the said shaft and extending upwardly therefrom, a prime mover mounted upon the said cross member and means connected to the said second arm and operatively connected to the prime mover, said last mentioned means being positioned substantially horizontally for the purpose described.

In testimony whereof I affix my signature.
GEORGE E. DEAN.
